[57] CLAIM

The ornamental design for a jewelry holder and display stand, as shown and described.

DESCRIPTION

FIG. 1 is a perspective view of a jewelry holder and display stand, showing my new design;

FIG. 2 is a top plan view thereof;

FIG. 3 is a bottom plan view thereof;

FIG. 4 is a right side elevational view, it being understood that the left side elevation is a mirror image thereof; and

FIG. 5 is a rear elevational view.

FIG. 1

FIG. 2

FIG. 3

FIG. 4

FIG. 5
